UNITED STATES PATENT OFFICE.

LUDWIG WILHELM SEESE, OF DELMENHORST, GERMANY.

PROCESS OF MAKING LINOLEUM PRODUCTS.

SPECIFICATION forming part of Letters Patent No. 728,997, dated May 26, 1903.

Application filed October 7, 1902. Serial No. 126,339. (No specimens.)

To all whom it may concern:

Be it known that I, LUDWIG WILHELM SEESE, a subject of the Grand Duke of Oldenburg, and a resident of Delmenhorst, in the 5 Grand Dukedom of Oldenburg, German Empire, have invented certain new and useful Improvements in Processes of Making Linoleum Products, of which the following is a full, clear, and exact description.

10 This invention relates to processes for making linoleum or the like which allow of the use of a lighter foundation material than was hitherto possible, and thus effect a great saving in the manufacture of linoleum. The 15 foundation material is, as is well known, mainly necessary in the manufacture (the rolling) of the coating or covering in order to give the necessary coherence to the covering substance in passing through the rollers, as 20 the mass or substance alone would not be capable of being rolled without such a foundation fabric. As the rollers exert a strong drag on the material rolled, it has hitherto been necessary to employ a suitably strong 25 foundation material capable of withstanding this strain. A much lighter foundation fabric is, however, sufficient for holding up the finished product than is previously necessary for the rolling process; and the object of the 30 present invention is to employ only such a light foundation fabric and to dispense with the previous large consumption of thick expensive foundation fabrics.

By the present invention in addition to the 35 light foundation fabric a second stronger material is passed, with the substance, through the rollers, and this material absorbs the pull exerted by the polishing-rollers, which run somewhat faster than the preliminary pressing-rollers, and therefore pull strongly, while the lighter foundation fabric runs over a 40 flexibly-mounted guide-roller and between the preliminary pressing-rollers and the polishing-rollers, so that it cannot be dragged by the polishing-rollers, and has to sustain 45 no strain during the rolling. The strong assistant material which receives the strain is again separated from the finished linoleum after it leaves the rolling device, and thus 50 no consumption of the same takes place; but it is merely an assistant material which may be used time after time. The use of this ma-

terial running simultaneously through the rolls also renders it possible to make in a very simple and cheap manner a linoleum or 55 floor-covering the under side of which has any desired roughness. This has only hitherto been attained by means of suitably ribbed or roughened rollers and the employment of a suitably rough or wide-meshed material to run simultaneously through the rollers, the inequalities of which are impressed during the rolling process into the underside of the covering or linoleum, and when the 60 fabric which has passed through the rollers 65 simultaneously with the linoleum is subsequently removed these inequalities leave roughnesses, corrugations, or the like in the linoleum.

The accompanying drawings are illustrative of forms of apparatus that may be employed in carrying out the process.

In the drawings, Figure 1 is a diagrammatic view showing the covering substance with its foundation fabric passed over an elevated guide-roller with the foundation fabric lying next to the material constituting the assistant fabric. Fig. 2 is a similar view showing the covering substance lying next to the assistant fabric or material. Fig. 3 is a 80 view similar to Fig. 2, showing the arrangement of the flexibly-supported guide-roller inverted—that is, below the plane of the pressing and polishing rollers.

In the accompanying drawings apparatus 85 is shown diagrammatically by which this process may be carried out.

a *a*, Fig. 1, are the preliminary pressing-rollers, and *b* *b* the polishing-rollers, which run somewhat quicker than the former.

c is the light foundation fabric employed in the process, and *d* is the strong assistant material, which runs simultaneously through the rollers. This assistant material *d* runs in a straight line from one pair of rollers to 95 the other and absorbs the strong pull which the polishing-rollers *b* exert on the material to be rolled. The light foundation fabric *c*, on the other hand, with the coating substance, which has been preliminarily impressed thereon, after passing through the preliminary pressing-rollers *a* runs over the guide-roller *f*, flexibly mounted by means of 100 springs or other suitable means, and from

this again to the polishing-rollers *b* in order to be polished by them in the ordinary manner. In the case of any pull exerted by the polishing-rollers *b* on the light foundation fabric *c* and the coating substance *g* the guide-roller *f* yields, so that this pull cannot affect the foundation fabric and the coating substance *g*, and therefore these are not subjected to any stretching, yet the flexibly-mounted guide-roller *f* always keeps tight the linoleum running over it. The drawings indicate how the strong material *d* is again removed from the finished linoleum after leaving the polishing-rollers *b*. If for this assistant substance *d* there be employed, as already mentioned, a suitably rough or wide-meshed fabric, these inequalities in passing through the rollers are pressed into the under side of the linoleum or covering and then a material is obtained having a suitably roughened, ribbed, or the like under side. The separate threads of the foundation fabric *a* are thus pressed into the covering substance by the inequalities of the assistant material *d*, so that they then lie embedded in the substance of the finished linoleum. The threads are thus protected against outside influences and in spite of their inherent strength are further strengthened by this embedding in the mass. By the impressing of the foundation fabric into the mass the fabric and the mass are made to adhere very strongly together, a property by which this improved floor-covering is favorably characterized in contrast to the products hitherto made, in which the foundation fabrics only lie flat on the covering substance. If, however, the linoleum is to have an ordinary smooth under side, it may be rolled in a reverse position, 40 the light foundation fabric *c*, as shown in Fig. 2, being not directly passed through the rollers over the assistant material *d* with the covering substance lying thereon; but the covering substance is scattered on the as-

sistant material *d*, and over this the light 45 foundation fabric *c* is placed, and then the whole is conveyed through the rollers. A very smooth fine assistant fabric *d* is in that case employed, which is easier released from the finished material after leaving the rolling apparatus and leaves a perfectly-smooth surface on the linoleum which then forms the upper surface of the finished product. The assistant fabric *d* may also be allowed to run through the rollers over the covering substance, the latter being thus allowed to rest on the light foundation fabric, and the assistant fabric fed over this, as shown in Fig. 3. The flexibly-mounted guide-roller *f* is then arranged beneath the roller-track instead of above it. The assistant fabric *d* is preferably formed as an endless band running over rollers, so that it constantly passes around between the pressing-rollers. The assistant or subsidiary fabric may be of any 65 suitable material—such, for instance, as wire-netting, sheet metal, or the like.

Having now described my invention, what I claim as new, and desire to secure by Letters Patent, is—

A process for making a linoleum product which consists in passing the covering substance simultaneously with two separate fabrics in sheet form between separate pressing and polishing rollers operating at different 75 relative speeds, one of said fabrics having the covering substance preliminarily pressed thereon, and the other fabric being a stronger assistant fabric which is arranged to absorb the pull of the polishing-rollers, and finally 80 separating the stronger assistant fabric from the finished product.

In witness whereof I have hereunto set my hand in presence of two witnesses.

LUDWIG WILHELM SEESEER.
